(57) **CLAIM**

The ornamental design for a “golf bag bottom plate”, as
shown and described.

DESCRIPTION

FIG. 1 is a perspective view of a golf bag bottom plate,
showing my new design;

FIG. 2 is a bottom plan view thereof;

FIG. 3 is a top plan view thereof;

FIG. 4 is a left side elevation view, the right side elevation
view being a mirror image thereof;

FIG. 5 is a rear elevational view thereof; and,

FIG. 6 is a front elevational view thereof.

The broken line environmental structure is for illustrative
purposes only and forms no part of the claimed design.
